UNITED STATES PATENT OFFICE.

JAMES E. GIBBS, OF DICKSON, TENNESSEE.

WOODWORKING-MACHINE.

1,104,791.

Specification of Letters Patent.

Patented July 28, 1914.

Application filed January 9, 1913. Serial No. 741,067.

To all whom it may concern:

Be it known that I, JAMES E. GIBBS, a citizen of the United States, residing at Dickson, in the county of Dickson and State 5 of Tennessee, have invented a new and useful Woodworking-Machine, of which the following is a specification.

The device forming the subject matter of this application is adapted to be employed 10 for cutting staves from a block of material.

One object of the present invention is to provide novel means whereby the block of material is released for transverse sliding movement, at the end of each stroke of the 15 carriage, thereby permitting the operator to advance the block of material transversely into the path of the cutting member.

Another object of the invention is to provide novel means whereby the movable grip 20 which engages the material may be released simultaneously with the stoppage of the movement of the carriage which advances and retracts the material longitudinally with respect to the cutting member.

25 Another object of the invention is to provide novel means for operatively connecting the carriage with a saw actuating shaft.

It is within the scope of the invention to improve generally and to increase the utility 30 of devices of that type to which the present invention appertains.

With the above and other objects in view which will appear as the description proceeds, the invention resides in the combination 35 and arrangement of parts and in the details of construction hereinafter described and claimed, it being understood that changes in the precise embodiment of the invention herein disclosed can be made within 40 the scope of what is claimed without departing from the spirit of the invention.

In the drawings—Figure 1 is a top plan; Fig. 2 is a side elevation; Fig. 3 is a fragmental longitudinal section on the line 3—3 45 of Fig. 1, parts appearing in elevation; Fig. 4 is a detail in side elevation, showing the trip mechanism in a different position from that depicted in Fig. 2; Fig. 5 is a transverse section on the line 5—5 of Fig. 2; Fig. 6 is a transverse section on the line 6—6 50 of Fig. 1; and Fig. 7 is a transverse section in the line 7—7 of Fig. 1.

In carrying out the invention there is provided a base 1 upon which are mounted 55 transverse supports 2 and 3.

Extended longitudinally of the machine

and journaled for rotation in the supports 2 and 3 is a saw shaft 4 supporting for rotation a tubular saw 5, the cutting end of which is indicated by the reference character 60 6. Upheld by the support 3 and extended therethrough and within the contour of the tubular saw 5 is a trough 7. Secured to the saw shaft 4 is a drive pulley 8, or other suitable means, whereby the saw shaft and the 65 mechanism operatively connected therewith may be actuated from a prime mover.

Secured to one end of the saw shaft 4 is a pulley 9 about which is trained a belt 10, the belt 10 being passed about a pulley 11 70 secured to a shaft 12, the shaft 12 being disposed parallel to the saw shaft 4. That end of the shaft 12 which is adjacent to the pulley 11 is mounted to rotate in a bearing 14 which is pivoted as indicated at 15 in a 75 bracket 16, the bracket 16 being attached to the support 2. The construction, therefore, is such that the shaft 12 may rotate and may have a slight transverse swinging movement. The shaft 12 is journaled at one end in a 80 bearing 17 which is mounted to slide in a guide 18 connected with the base 1 or supported in any other suitable manner.

Fixed upon the shaft 12 is a friction wheel 19 adapted to bear against a friction disk 20 85 secured to a shaft 21 which extends transversely of the shafts 12 and 4. The shaft 21 is journaled in bearings 22 upheld by brackets 23, the brackets 23 being attached to the base 1.

90 Fixed to the base 1 is an arm 24 constituting a fulcrum for a lever 25. The lever 25 is connected by means of a link 26 with the sliding bearing 17. A spring arm 27 (indicated in Fig. 1) is attached to the base 1 95 and bears against the inner edge of the lever 25 so as to hold the friction wheel 19 normally out of engagement with the friction disk 20. A connecting member 28, which, wholly or in part, may be flexible, is united 100 with the free end of the lever 25 and extends over a pulley 29 (see Fig. 6) supported by an arm 30 connected with a brace 31 extended between tracks 32, the tracks 32 being upheld by the supports 2 and 3, and 105 extending the full length of the machine. One end of the connecting member 28 is united as indicated at 33 (Fig. 2) with the intermediate portion of a lever 34, extended longitudinally of the machine and fulcrumed 110 as indicated at 35 upon the support 3. The free end of the lever 34 is mounted to recip-

rocate in a slot 36 formed in a post 37 secured to the base 1, the post 37 being provided with a horizontal extension 38 which is connected with the tracks 32 at one end thereof. The free end of the lever 34 is drawn upwardly by a retractile spring 39, the upper end of the spring 39 being assembled with the tracks 32 (Fig. 5). The upward movement of the free end of the lever 34 is limited by the engagement between the free end of the lever and the upper end of the slot 36 in the post 37. A pedal 40 extends transversely of the machine and is fulcrumed as indicated at 41 upon the base 1. 10 An adjustable connection 42 unites the pedal 40 with the lever 34. The lever 34 is provided with an offset arm 43 and a connection 44 unites the arm 43 with one end of a brake lever 45, fulcrumed intermediate its ends as 15 indicated at 46 upon one of the tracks 32, one end 47 of the lever being adapted to bear against a wheel 48 which is secured to one end of the shaft 21. A retractile spring 49 is connected with the brake lever 45 and 20 serves to hold the end 47 of the lever in engagement with the wheel 48, the lower end of the spring 49 being united by means of a connection 50 with the base 1, the connection, as shown in Fig. 2, including a screw-held, slotted part, so that the tension of the 25 spring may be adjusted.

Mounted to reciprocate upon the tracks 32, longitudinally of the machine, is a carriage, the carriage being a composite structure. The carriage comprises cross heads 51 and 52, (Figs. 5 and 7) the cross heads supporting wheels 53 which are adapted to engage the tracks 32. The cross heads 51 and 52 are united by means of rods 54. Each 30 cross head is equipped with a depending bracket 55 mounted to slide upon a guide rod 56, the guide rod 56 being supported in braces 56^a which connect the tracks 32. A pitman 57 is operatively united, through the 35 medium of an adjustable connection 58, with the wheel 48, the pitman being pivoted to a laterally extended arm 59, the arm 59 being supported by one of the rods 54 which extend between the cross heads 51 and 52.

50 The cross head 52 (Fig. 3) is provided with a longitudinal guide way 60 in which a rack bar 61 is mounted to slide. A retractile spring 62 (Figs. 1 and 2) is connected with the rack bar 61 and is connected with a 55 retaining plate 63, adjustably held by means of a screw 64 or the like upon the cross head 51. The cross head 52 is provided with up-standing ears 65 (Fig. 1) in which is journaled for rocking movement, a shaft 66 60 provided with a pinion 67 (Fig. 3) which meshes into the rack bar 61. Projecting from the shaft 66 is an arm 68. The downward swinging movement of the arm 68 under the action of the spring 62 is prevented 65 by a stop lug 69 which upstands from one

end of the rack bar 61. The rack bar 61 carries a laterally projecting grip 70 adapted to coöperate with a grip 71 which is fixed to one of the rods 54 (as shown in Fig. 1). Secured to the cross head 52 through the medium of a screw and slot union 73' is an arm 72 which supports a wheel 74. 70

A link 75 (Fig. 4) is pivotally connected with the lever 34, the upper end of the link 75 being pivotally connected with an upright lever 76 which is fulcrumed as shown at 77 on the extension 38 of the post 37. The lever 76 is provided with a vertically adjustable finger 78 lying in the path of vertical movement of the arm 68. A trip 80 79 is pivoted as indicated at 80 to the extension 38, the trip 79 carrying a roller 81 which is located in a common vertical plane with the finger 78 and the arm 68. The swinging movement of the trip 79 is limited 85 by a stop block 82 carried by the extension 38. A lever 83 is fulcrumed as indicated at 84 upon the extension 38, the lever 83 carrying a lateral finger 85 which is engaged behind the trip 79 so as to swing the trip toward 90 the stop block 82, the lever 83 being counter-weighted, as indicated at 86, so as to actuate the trip 79.

The rods 54 which connect the cross heads 51 and 52 support inclined guides 87 slanting toward a stop 88, the stop 88 being supported by brackets 89 connected with one of the tracks 32. 95

In practical operation, the tubular saw 5 is rotated continuously by the shaft 4 and 100 the drive pulley 8. The shaft 4, through the medium of the pulley 9, the belt 10 and the pulley 11 drives the shaft 12 continuously. The shaft 12, however, does not 105 drive the shaft 21 continuously, because the spring arm 27, bearing against the lever 25, retracts the slidale bearing 17 on the guide 18 through the medium of the link 26, the friction wheel 19 thus being held out of engagement with the friction disk 20, the 110 shaft 12 having a slight transverse swinging movement with the pivot element 15 as a center. When however, the foot of the operator is placed upon the pedal 40, the pedal is tilted and the connection 28 is operated, 115 drawing the free end of the lever 25 inwardly and sliding the bearing 17 and the shaft 12 until the friction wheel 19 bears against the friction disk 20. When the shaft 12 is operatively connected with the 120 shaft 21 and when the shaft 12 is rotated in the manner hereinbefore described, rotary movement will be imparted from the shaft 21 to the wheel 48, the wheel 48 through the medium of the pitman 57 causing sliding 125 movement in the carriage comprising the cross heads 51 and 52 and the rods 54 which connect the cross heads. It is to be observed that so soon as the lever 34 is swung through the medium of the pedal 40, the 130

connection 44 will tilt the brake lever 45 upon its fulcrum 46 and withdraw the end 47 of the lever 45 from engagement with the periphery of the wheel 48 so that the 5 wheel 48 is set free for rotation.

The strip of timber from which the staves are to be cut is placed upon the guides 87 in abutment with the stop 88. The ends of the stick of timber are held between the 10 grips 70 and 71, the grip 71 being fixed and the grip 70 being actuated by the spring 62 to hold the stick of timber in place. When the carriage is reciprocated, the stick of timber is brought in contact with the 15 cutting end 6 of the tubular saw 5 and a stave is cut off, the stave dropping upon the trough 7, from which the stave may be removed, the trough, if desired, being inclined so as to discharge the stave. When 20 the carriage moves to the left during the cutting operation, the trip 79, being actuated by the counterweighted lever 83, swings to the left and rests upon the stop block 82, the roller 81 on the trip being lowered so 25 that it lies below the lower edge of the arm 68. When the carriage moves to the right, the roller 74 on the arm 72 engages the trip 79 and raises the roller 81, the latter raising the arm 68 and the pinion 67 actuating 30 the rack bar 61 to draw the grip 70 from one end of the bolt of timber. The bolt of timber is now free and will slide along the guides 87 against the stop 88 thereby to position a new part of the bolt 35 in the path of the saw 5. Ultimately, the trip 79 is forced so far to the right by the action of the roller 74 that the roller 81 on the upper end of the trip no longer lies beneath the arm 68. Then the rear end of 40 the arm 68 drops, partly due to the weight of the arm and partly due to the action of the spring 62, the latter moving the rack bar 61 to the left and causing the grip 70 to engage again with the end of the bolt of 45 timber. The carriage now moves to the left and a new section is sawed off the bolt. During the operation above described, that is while the saw is rotating, the carriage moving and the trip swinging to and fro, 50 the lever 34 is held depressed. Both Figs. 4 and 2 show the lever 34 elevated, the machine in Fig. 4 having been stopped at a point intermediate the ends of the stroke of the carriage, in order to show the relative 55 positions of the parts of the machine. Fig. 4 shows the parts as they will appear when the machine is running, saving for the fact that under such circumstances the lever 34 will have been depressed so as to swing 60 the lever or detent 76 to the right and to move the finger 78 out of the path of the arm 68. Now suppose that the operator desires to place a new bolt of timber on the 65 guides 87 while the machine is at rest. In order to do this the movable grip 70 of

course must be in a retracted position. To effect the end in view, the operator removes his foot from the pedal 40 as the roller 81 on the trip 79 is passing from beneath the rear end of the arm 68. Then the spring 39 pulls the lever 34 upwardly, the link 75 tilts the levers 76 and the finger 78 moves to the left and passes beneath the roller 81 and beneath the rear end of the arm 68, the roller 81 acting as a guide which serves to direct the rear end of the arm 68 onto the finger 78. The machine then stops with the parts in the positions shown in Fig. 2 and referring to Fig. 3 it will be obvious that the grip 70 will have been retracted away 70 from one end of the old bolt. The old bolt may now be taken out and a new one may be inserted. When the lever 34 is depressed to start the machine, the detent lever 76 is 75 swung to the right at its upper end, withdrawing the finger 78 from beneath the roller 81 and from beneath the rear or right hand end of the arm 68. The trip 79, being actuated by the counterweighted lever 83, swings to the left against the stop lug 62 80 and the arm 68 drops onto the stop lug 69. 90

Having thus described the invention, what is claimed is:—

1. In a device of the class described, a cutter; a carriage mounted to move adjacent to the cutter; a fixed grip on the carriage; a movable grip on the carriage; a movable member on the carriage and operatively connected with the movable grip to retract the grip; means for actuating the 95 movable member; a detent movable into the path of the movable member to hold the movable grip retracted; means for actuating the cutter; means for actuating the carriage; and a device for coupling up and disconnecting the two actuating means, said device being operatively connected with the 100 detent to move the detent into the path of the movable member simultaneously with the disconnecting of the two actuating 105 means. 110

2. In a device of the class described, a cutter; a carriage mounted to move adjacent to the cutter; a fixed grip on the carriage; a movable grip on the carriage; a movable member on the carriage and operatively connected with the movable grip to retract the same; a detent movable into the path of the movable member to hold the 115 movable grip retracted; means for actuating the cutter; means for actuating the carriage; a device for coupling up and disconnecting the two actuating means, the said device being operatively connected with the 120 detent to move the detent into the path of the movable member simultaneously with the disconnecting of the two actuating means; and a pivoted trip actuatable by the carriage and coacting with the movable member to actuate the movable member, the trip constitut- 125 130

ing a guide for directing the movable member onto the detent.

3. In a device of the class described, a supporting structure; a carriage mounted to 5 reciprocate on the supporting structure; a fixed grip on the carriage; a movable grip on the carriage; a movable member operatively connected with the movable grip; a trip pivoted to the supporting structure and 10 coacting with the movable member to actuate the latter; and means on the carriage for actuating the trip.

4. In a device of the class described, a supporting structure; a carriage mounted 15 to move thereon; a fixed grip upon the carriage; a movable grip upon the carriage; a movable member operatively connected with the movable grip; a trip pivoted to the supporting structure and coacting with the 20 movable member to actuate the same; means on the carriage for actuating the trip; and a detent upon the supporting structure and movable into engagement with the trip and the movable member.

25 5. In a device of the class described, a supporting structure including a stop; a

trip pivoted to the supporting structure and adapted to rest upon the stop; means for moving the trip toward the stop; a carriage mounted to move upon the supporting structure; a fixed grip on the carriage; a movable grip on the carriage; a movable member mounted on the carriage and operatively connected with the movable grip, the movable member lying above the trip; and 30 means on the carriage for engaging the trip to elevate the trip and to cause the latter to elevate the movable member; and a movable detent mounted upon the supporting structure and supporting the trip and movable member to maintain the movable grip retracted, the trip constituting a guide adapted to direct the movable member onto the detent.

35 In testimony that I claim the foregoing as 40 my own, I have hereto affixed my signature in the presence of two witnesses.

JAMES E. GIBBS.
